SPARK GAP MECHANISM

Godfrey P. Goode, Covington, Ky., and Carl K. Gieringer, Cincinnati, Ohio, assignors to The Liebel-Flarsheim Company, Cincinnati, Ohio, a corporation of Ohio

Application October 28, 1948, Serial No. 57,026

22 Claims. (Cl. 250—38)

1

This invention relates to spark gap mechanisms of the type adapted for operation in conjunction with charged condenser circuits for producing high frequency electrical energy. Such apparatus is employed in radio transmission and for other purposes, but the invention is particularly useful in high frequency spark gap machines for surgical and therapeutic purposes and, therefore, is disclosed essentially in that environment.

A spark gap mechanism consists of one or more pairs of spaced electrodes which are charged electrically for the emanation of sparks between them. These sparks are intensely hot and, although metals of heat-resistant or refractory nature have been utilized in fabrication of the electrodes, still, even such materials are pitted and become worn away during usage of the apparatus. The spacing of the electrodes, that is, the width of the spark gap determines the voltage of the electrical energy which is provided from the mechanism. In general, the spark at a wide gap is hotter than at a narrow gap, and therefore exerts a greater deteriorating effect upon the electrodes between which it is produced.

Various devices are available which respond to the heat of the sparks to compensate for expansion and thereby maintain uniformity of gap width throughout a given period of operation of the apparatus. However, these devices are incapable of providing adequate compensation for the wearing away of the electrodes and, in surgical and therapeutic spark gap oscillators, it is highly desirable that gap width uniformly may be maintained, or readily obtained, in the day to day use of the equipment, since the characteristics of the discharge current from the apparatus otherwise will change.

This invention contemplates a spark gap mechanism capable of providing uniform gap spacing throughout the life of the electrodes or the apparatus. Otherwise expressed, a primary objective has been to provide an apparatus in which the electrodes conveniently may be set, or reset from time to time, to assume predetermined gap width positions. Such adjustments may be made conveniently as an incident to placing the apparatus into electrical operation.

A suitable spark discharge may be obtained by the use of a single pair of electrodes, spaced a substantial distance apart from one another. Such an apparatus commonly is called a "single gap" device. However, more satisfactory results are usually obtained if the machine comprises a 55

2

series of gaps constituted by a plurality of pairs of electrodes connected electrically in series. In such cases, the gap widths are smaller, and, since the sparks are shorter, the electrodes suffer less deterioration. In mechanism of this type, it is highly desirable that all of the gaps be of uniform width; otherwise, that pair of electrodes which is most widely spaced will produce a different discharge voltage than a pair which is spaced closely, and will suffer more surface pitting to aggravate the condition as time goes on.

In recognition of these inequalities, which generally exist in apparatus now available, it is an objective of the present invention to provide a mechanism for uniformly spacing all of the respective electrodes in a series of pairs, one from another, such that spark gaps of equal width, which they then delineate, will produce discharge currents of uniform characteristics. Also, even though one or a series of spark gaps initially may be of the desired width and uniformity of width, still, during a period of electrical operation of the equipment, some electrodes will inherently be worn, pitted, or deteriorated more than others, and even though a machine initially conforms to optimum conditions, these conditions will vary from optimum during periods of usage. Therefore, it is an objective of the invention to provide a simple apparatus for resetting the gap widths such that optimum conditions of gap width may be restored or re-established periodically.

Other objectives and features of the invention are described at later points in this specification in relation to characteristic conditions normally encountered in the operation of the apparatus, and, therefore, are not described in detail at this point.

Briefly, this invention is predicated upon the concept of establishing a predetermined spark gap space between a pair of electrodes by moving one or the other or both electrodes of the pair through a predetermined distance, from a position of engagement thereof. Otherwise expressed, engagement of the electrodes is utilized as a standard or reference point from which gap width is measured, or from which the separating movement is initiated, since this standard remains constant no matter how the electrodes may have been worn while they were spaced apart during any preceding period of operation.

Having the electrodes in engagement, they are separated a predetermined distance by the movement of a shifter which is adapted to be actuated through a predetermined fixed distance.

This fixed distance of movement of the shifter may be equal, or proportional, to the gap width through which the electrodes are to be spaced apart. However, the electrodes, in engagement, will occupy different positions in space, depending upon the degree to which one or both may previously have been worn away. Hence, a direct, positive coupling between the shifter and one or both of the electrodes, through which they may be moved, is not feasible. In accordance with the present invention, the means for separating the electrodes one from the other is coupled actively with the shifter after the electrodes have been brought into engagement, such that movement of the shifter thereafter will provide the desired gap width. Such couplings herein are termed wear compensators; they assume coupling positions between the shifter and the means by which the electrodes are spaced, depending on the wear condition of the electrodes and thus discriminate, by the positions they assume, for the wear of the electrodes which previously may have occurred.

In the preferred embodiment of the invention, these wear compensating couplings are in the form of cams or wedge-shaped elements and a device is provided for holding them out of the way, to permit the electrodes to seat firmly against one another, after which the wear compensators are released co-actively to couple the electrode moving means with the shifter. Each pair of electrodes constituting a gap is served by an individual compensator. Therefore, whether the machine embodies one gap or a plurality, the movement of the shifter through a fixed distance will cause a predetermined gap width to be established.

The shifter in the preferred embodiment is actuated manually by a resetting knob or lever through which the gap electrodes may be reset from time to time. Most technicians, having cause to operate a knob or lever of this type, will move it very quickly. However, in accordance with the present invention, an interlock is provided to delay the coupling of the shifter with the means for moving the electrodes until such time as the electrodes have engaged one another firmly and the wear compensating couplings have assumed their co-active or operative positions of engagement. In daily practice, a doctor or technician may utilize an electro-surgical machine of the type served by the present spark gap mechanism many times throughout the day. Each time he does so, the gaps readily are resettable to insure the delivery of electrical energy having the same characteristics as that provided in a preceding period of operation. Since resetting of the gap width proceeds from the reference condition in which the electrodes are in engagement with one another, the resetting is caused to take place conveniently as an incident to the placing of the machine into electrical operation, and the apparatus, therefore, is not dependent upon the special attention of the operator in respect to gap adjustments.

A typical machine constructed in accordance with these principles is illustrated in the drawings in which:

Figure 1 is an elevation of the apparatus looking at the end at which the control knob is located.

Figure 2 is a side elevation.

Figure 3 is a top plan view showing the wear compensator in various positions corresponding

5 to the wear conditions of the various electrodes of the apparatus.

Figure 13 is a longitudinal sectional view taken on the line 13-13 of Figure 6, and

Figure 14 is an enlarged sectional view showing the relationship of the parts of an electrode spacing assembly.

The apparatus shown in the drawings consists essentially of one or more pairs of cooperating spark electrodes indicated generally at 1 and 2 which are adapted to be separated from one another by a linkage indicated generally at 3. This linkage is actuated from a shifter member, indicated generally at 4, which responds in movement to the actuation of a knob or handle indicated generally at 5. The wear compensating keys, one for each pair of electrodes, are indicated generally at 6, while an interlock 7 is associated with the shifter member.

The spark gap apparatus which is herein illustrated embodies four pairs of spark electrodes connected electrically in series, and the wear compensating mechanism not only insures predetermined spacing as to any pair of electrodes but also insures uniformity of spacing from pair to pair. However, as previously described, the present invention is adapted to be used in conjunction with a single gap machine, for the purpose of insuring accuracy in the spacing of the electrodes throughout their useful life, or—may be employed in conjunction with a plurality of electrodes different in number or arrangement from that disclosed in the drawings. It is also to be understood that the apparatus is adapted for use in conjunction with thermo-compensating mechanism of the type disclosed in U. S. Patents No. 1,698,157 and 1,791,464 whereby heat incidental to sparking does not effect gap width.

65 In the apparatus disclosed, end plates 10 and 11 are traversed by support rods 12 and 13. These are arranged in spaced relationship to one another at the corners of the end plates, and are surrounded respectively by insulator tubes 14 which extend throughout their length. The rods 13 and the insulator tubes pass through insulator bushings 15 at the exterior faces of the end plates 10 and 11; and portions of the support rods extending beyond the bushings are threaded to carry nuts 16 which bear on washers 17.

At spaced intervals intermediate the end plates 10 and 11, the insulator tubes 14 pass through pairs of radiator plates 20 and 21, the plates of the respective pairs being separated from one another by insulator bushings 23, preferably of ceramic material. Each radiator 20 is in electrical interconnection with the radiator 21 of the next gap through an electrically conductive bushing 25 which has its endwise portions bearing facially against the respective radiator plates. Radiator 20 of the pair at one end of the series is in electrical connection through a conductive bus strap 26 which is mounted over insulator tube 14. This strap in turn is insulated from the adjacent end plate 10 by means of a ceramic insulator bushing 27. Radiator 21 at the opposite end of the series is in electrical connection, through an electrically conductive bushing 28, with a bus strap 29 which, in turn, is insulated from the adjacent end plate 11 by means of an insulator 30. The spacers and bushings and radiators occupy the entire length of the tubular insulators 14 between the end plates and it will be seen therefore that the nuts 16 serve to clamp all of these members into rigid assembly. Terminal straps 26 and 29 project sidewise from the assembly where they are bent to facilitate interconnection of electrical leads to the apparatus.

The upper portions of the radiator plates 20 are free and these plates are therefore bendable or yieldable. For convenience, they may be termed movable radiators. However, these plates are provided with edge flanges 31 since it is preferable that they be made of copper for conductive and radiating purposes and might tend to lose their resiliency over a period of time.

On the other hand, radiator plates 21 extend upwardly beyond the edges of the movable radiators and are traversed at their upper portions by spaced tubular insulators 33, which carry draw rods 34 having nuts 35 at their endwise portions, similar to those at the bottom of the machine. Spacing insulators 36 extend respectively over the insulator tubes 33 between the respective radiators, and between the end plates and the next adjacent radiators, to hold them all in fixed spaced relationship to one another.

Each radiator 21 carries a spark electrode 37 and each movable radiator carries a cooperating spark electrode 38. The faces of these electrodes are preferably crowned, as shown in Figure 2, and they are of such length that they normally engage one another when the movable radiator plates are in relaxed position. However, these electrodes, during operation of the mechanism are spaced apart for the emanation of sparks between them. From the electrical interconnections previously noted, it will be seen that current may pass from one of the terminals 26 or 29 through the radiator plate which is in connection with it, to its electrode, then across the gap to the adjacent electrode, from this through a conductive bushing to the next radiator and gap, and so on through all of the gaps to the other terminal.

Any suitable mechanism may be employed for moving one or both of the electrodes such that they may be spaced appropriately one from another. In the embodiment of the invention shown in the drawings, the linkage 3 is employed for this purpose, to force the radiator plates 20 away from the stationary radiators 21 and thereby separate the contacts. Thus, the stationary radiators 21 are equipped with bracket pieces 39,

which are spaced from one another to provide a clevis which carries a pivot rod 40. The latter is held against axial displacement by collar washers 41. Pivot 40 passes through levers 42, one lever for each gap, and, above each bracket 39, each stationary radiator carries a guide bushing 43 which may be press fitted into place, as shown in Figure 14. This bushing in each gap assembly is bored to receive a driving pin 44, having one crowned end bearing against lever 42 while an opposite crowned end bears against the face of a ceramic insulating button 45. The button has a shank portion which is press fitted into a bore in the adjacent movable radiator plate 21. As the lever is moved it pushes the pin 44 which in turn pushes the movable radiator 20 away from the stationary plate 21 and thereby separates the electrodes 37 and 38 which are carried respectively by the radiators.

The resilience of the movable radiator plates is probably adequate to return electrodes 37 and 38 into engagement with one another when the lever 42 is free. However, as an extra precaution, such return positively may be effected by the supplemental mechanism which is shown in Figure 14. This consists of a draw rod 48 which passes through insulator bushings 49 and 50 mounted at opposed faces of the respective radiator plates 20, 21. The draw rod has heads 51, 51 at its ends, these being engageable with the outer faces of the bushings 49 and 50. A compression spring 52, surrounding the rod 48, has one end seated against the face of bushing 50 while the opposite end bears against a washer 53 which abuts the adjacent head 51 of the rod. The spring is compressed when the electrodes are separated, and therefore urges them to engaged position.

The end plates 10 and 11 are flanged outwardly at their upper edges, as at 55 (Figures 2 and 6). Elongated angle members 56, arranged in spaced parallel relationship to one another, extend across the end plates 10 and 11, and are fastened in place on the respective endwise flanges 55 by means of screws 57, carrying washers 58 and nuts 59.

The upstanding walls of the angle members 56 constitute guides for the shifter member indicated generally at 60. This, preferably, is in the form of a channel 60, of such width that its side walls extend upwardly adjacent the upstanding flanges of the angle members 56. For guide purposes, the vertical walls of the angles 56 have grooves or depressions 61 provided at their inner faces. These are in longitudinal alignment with one another and they provide linear races for ball members 62. One side wall of channel 60 contains recesses 63 for supporting the balls in engagement with the cooperating guide grooves 61. However, the other side of the channel member 60 carries resilient leaves 64 which are configurated to urge the balls seated therein toward the adjacent guide grooves (Figure 8). This construction provides substantially frictionless movability of the shifter member 60, and at the same time eliminates any sidewise looseness in the assembly. Shifter channel 60 is slotted longitudinally as at 69 and the upper endwise portions of the linkage levers 42 extend through the slots.

An elongated bracket 65 is mounted at the bottom face of one of the angle members 56 to mount a plurality of leaf springs 67, which are fastened as at 68 and which extend resiliently into engagement with the edges of the levers 42 near the upper portions thereof. The springs

serve to hold the levers against the push rods 44, such that the various parts of the spark gap separating linkage are always operative without loss of motion.

The shifter 4, constituted by channel 60 in the embodiment disclosed, occupies two different functional positions corresponding respectively to operative spacing and non-operative engagement of the spark electrodes. In the present apparatus, it is moved manually to operative position and is returned or retracted by spring pressure, although an opposite construction is equally suitable. The details of the manual actuator appear at a later point. The details of the retracting apparatus are as follows:

One end plate, 10, of the assembly, is equipped with a mounting bar 70, which projects upwardly between the angles 56, as shown in Figure 7, through a slot or opening 72 in the bottom web of the shifter channel 60. Within the channel area, the mounting bar carries a screw 74 which extends longitudinally of the shifter bar. This screw is held in fixed position, once adjusted, by means of a lock nut 75 which binds against the face of the mounting bar 70 into which the screw is threaded. The shifter channel 60 carries an arm 76, which is slotted so as to clear the screw shank, and a compression spring 77, surrounding the shank of the screw, has its one end abutting the lock nut 75 while the other abuts a washer 78 which in turn bears facially against the arm 76 of the shifter channel. Hence, the compression spring always urges the shifter toward its retracted position, but such movement is limited by abutment of the arm 76 against the head of the screw 74. This screw may be adjusted to vary the point at which the shifter comes to rest on the point from which it is caused to move in opposite direction.

An operating rod 20 extends along an outer face of an end plate of the apparatus and through a suitable opening 81 in the bottom web of the shifter channel. The shaft is rotatably journaled in bores provided in arms 82 and 83 of a bracket which is mounted on the end plate of the assembly, the bracket being fastened by screws 85 which pass through the end plate into threaded engagement with bar 70 at the inside of the end plates so as to hold both in fixed position. Collars 86, 86 are provided on the shaft at the opposite sides of one of the arms, 83, and the shaft also passes through a guide bushing 87 which is fixed upon the other of the bracket ears 82. This shaft, therefore, is rotatable in the arms of the bracket and is held against longitudinal displacement.

Intermediate the side walls of the shifter channel 60, the operating shaft 20 carries a shifter cam 88 configurated to provide a throw portion 89 at a portion of its periphery while the balance of the periphery includes a non-operative dwell. The cam cooperates with a roller shaped follower 91 which is rotatably mounted upon a stud 92 projecting from the bottom web of the shifter where it is held by means of a nut 93. When the shifter is in retracted position, normally, the dwell portion of the cam is just out of engagement with the follower; that is, when the arm 76 of the shifter is in abutment with the head of the screw 74. However, rotation of actuating knob 5, which is fixed to the rod 20, will cause the throw 89 of the cam to engage the roller and move the shifter against the bias of spring 77.

Motion of the shifter, in the manner just described or by other suitable means, is transmitted

to the spark gap linkage levers 42 through the wear compensators or keys indicated generally at 6. It is the function of these elements to provide co-active engagement between the shifter member and the spark gap linkages, but also to discriminatively adjust themselves to compensate for wear which has occurred upon the electrodes.

The wear compensators or keys 6 of the present apparatus function to provide a uniformity of spacing at all times, whether one or a plurality of spark gaps are employed in the mechanism by coupling the shifter with the electrode spacer linkage when the electrodes are in the reference condition in which they engage one another. In the embodiment disclosed in the drawings, the wear compensators are provided for each pair of electrodes, and these units are in the form of self-adjusting or discriminating cams or wedges which are carried by the shifter, but which are biased to move into engagement with the levers 42 when they are permitted to do so, and when the levers are in positions corresponding to engagement of the electrodes. Each compensator mechanism, as shown in Figures 7 and 11, comprises a stud 95, located in the shifter channel 60 between the side walls thereof, and extending into threaded engagement with a T nut 94 in the bottom web of the shifter channel. The stud 95 carries a nut 96 which bears upon a washer 97 at the one face of the channel web for locking the stud, in any position of initial adjustment, against the T nut 94 at the other side of the channel. Stud 95 in each compensator assembly carries a washer 98 adjacent its head, and a spool 99 is rotatably mounted upon the stud between the washer 98, and another washer 99a, which is adjacent the face of the lock nut 96. A compensator cam 100 is fixed to the spool 99, as disclosed in Figure 12. The cam is generally of spiral configuration, made of light weight material and has a flange 101 bent up from its outer periphery to provide an operating face of adequate width.

A hair-type spring 102 is wound around the spool of each assembly and one end of the spring is hooked to the cam, as at 103, while the opposite end of the spring is hooked through an ear 104, bent laterally from an edgewise portion of the shifter channel 60. The spring, therefore, in the arrangement shown, biases the cam in counter clockwise direction.

The compensator assemblies just described are arranged respectively, adjacent linkage levers 42 whereby the edges of the cams are engageable with the edges of the linkage levers at the portions of the latter which project through the slots 69 in the shifter channel 60. It is to be noted that the cams are so positioned on the shifter that the leads or portions of least radius are spaced slightly away from the edges of the linkage levers 42 when the levers are in positions corresponding to engagement of the electrodes. For convenience, this may be termed the starting position of the shifter, or the non-operating position of the mechanism.

When a compensator 100 is allowed to adjust itself under the influence of its actuating spring 102, it will move until its periphery, which is of gradually increasing radius, engages the edge of linkage lever 42, which it serves, thereby operatively coupling the lever with the shifter. The cam actuating spring is of course incapable of driving the cam beyond this point against the bias of spring 52, or against the resilience of the radiator plates 20, regardless of the compounding of

forces which is provided in the linkage system. In other words, each cam rotates until it assumes a position of working engagement with the lever, without actually moving the lever.

When the compensator cams key the levers to the shifter in the manner just described, movement of the shifter will effect uniform movement of all of the levers and, therefore, all of the electrodes will be separated uniformly. Since the throw of the cam shifter 88 causes movement of the shifter through a predetermined or fixed distance, each, or all, of the electrodes will be spaced a distance which is the same as, or proportional to, such fixed distance, depending upon the nature of the linkage system. In the machine shown, the ratio of movement in the linkage system is approximately 5 to 1. The spark gaps desirably are approximately .001 inch in width, and the cam throw is such that the shifter moves the upper ends of the lever approximately .005 inch. The ratio, of course, readily may be varied to suit the intended construction and to suit the gap widths to be employed.

It is desirable, as an incident to resetting of the mechanism, to disengage the compensating cams from the levers, so that the levers, being released, will permit the electrodes of each pair to come to rest in full engagement under the biasing forces which urge them together. For this purpose, a cam shifter is utilized which, in the preferred construction, is actuated from the control knob 5 when the latter is moved toward off or non-operating position, that is, when it is moved in a clockwise direction in the apparatus illustrated. The cam shifter is in the form of an elongated bar 110 (Figures 9 and 11) which extends along the bottom web of the electrode shifter channel 60. This bar is guided longitudinally, at its one end, by a screw 111, which passes through a suitable slot 112 in the bar into threaded engagement with the bottom web of the electrode shifter channel 60. The other end of the cam shifter 110, carries a square or rectangular guide boss as indicated by the dotted lines 113 in Figures 3 and 7, which rides in a slot 114 cut into the shifter channel 60. Cam shifter bar 110 includes a longitudinal upstanding flange 114, to which a series of fingers 115a are fastened by means of screws 116 and nuts 117, one finger for each wear compensating cam. These fingers project laterally from the cam shifter bar for engagement with respective shoulders 120 which are provided on the wear compensating cams 108, intermediate the lead and terminal portions thereof. The fingers 115a also are of a somewhat elongated nature to provide faces 118 against which the endwise portions of the cam shoulders rest after the cams have been backed-away or shifted to their starting positions by the fingers.

The cam shifter bar 110 is moved, to accomplish these functions, by means of a lever arm 122 (Figure 4) fastened upon the control rod 80 so as to swing with it and thereby cause the arm to engage a stud 124 projecting from the shifter bar. Arm 122 is located upon the shaft 80 against a bushing 125, the latter having its opposite end located adjacent the operating rod guide bushing 87. Rotation of the control knob 5 causes the lever 122 to push the stud and move the cam shifter bar longitudinally in its guide slots 112 and 114. When the shifter bar 110 is actuated in this manner, the fingers 115a engage the cam shoulders 120 and thereby rotate the cams in the direction effective to cause their

peripheries to back away from the linkage levers 42. The cam shifter bar is urged in an opposite direction by means of a tension spring 128 having one end hooked to an ear 129 projecting upwardly from an end of the main shifter channel 60, and its opposite end hooked to an ear 130 of the cam shifter bar. Retracting movement of the cam shifter bar, when permitted, is limited by abutment of the end of the bar against the ear 129.

The relative position of the parts when the fingers 115a are holding the cams in their retracted or starting positions is shown in Figure 9. When the lever 122 releases the stud 125, the shifter bar moves backwards and the cams start to rotate, the shoulder surfaces 120 thereof relatively following the fingers 115. The cam peripheries thus approach and eventually engage the linkage levers.

Control knob 5 conveniently serves both the main shifter channel 60 and the secondary shifter 110 carrying the fingers 115a by which the wear compensators are retracted and released, the parts being so arranged that these motions occur sequentially, whereby the shifter channel 60 is moved after the compensators are released.

The control knob 5 manually may be moved very rapidly; in fact, the average operator tends to reset the mechanism by giving this knob merely a sharp twist in the proper direction. Such rapidity of movement may cause the actuation of the shifter 60 before the levers have assumed rest position, or before the compensating cams have reached operative positions of engagement with the levers. In this event, the full compensating function of the apparatus would not be exercised. However, the interlock mechanism, indicated generally at 7, is utilized to avoid this circumstance by preventing the actuating knob from moving the shifter until a momentary period of time has been allowed to elapse during which the compensating cams are moving into position.

In the preferred embodiment, in this respect, a dash-pot cylinder 132 is mounted on a bracket 133 (Figures 1, 2 and 6), the bracket being fastened in place by the same screws 85 which hold the bracket 34 for the operating lever 80. The dash-pot carries a piston 135 which is mounted at the end of a piston rod 136 having spaced collar washers 137, 137 at its outer endwise portion. An ear 138, mounted on the bottom of the bar 110, engages the piston rod 136 intermediate the washers 137 to interconnect the bar 110 with the dash-pot device. The dash-pot causes the cam shifter bar 110 to move slowly, under the influence of spring 128, and during such movement, the compensating cams gradually assume their operating positions.

In addition to the apparatus just described, the interlock comprises a lever 140 which is rotatably mounted on the operating rod 80, but operated by it through lost motion connections. Thus, lever 140 comprises two arms 141 and 142 projecting from the operating rod 80 in opposite directions. Cam shifter member 110 carries an interlock obstruction wall 143, which is movable with it, and one of the arms 141 of the lever 140 is equipped with a tail 144 projecting from its outer extremity that engages or abuts the obstruction wall when the lever is swung, unless the movement of the cam shifter 110 has been such that the tail 144 may pass the end of the obstruction,

Lever 140 is moved from the operating rod 80 by means of a pin 145 extending from the lever 122, which, as previously described, is fixed to the operating rod. This pin bears upon an edge of the arm 142 of the lever 140 to carry the latter with it. In this manner, the tail 144 is caused to approach the obstruction wall 143 as the knob 5 is rotated. Bearing in mind that rotation of the knob 5, in counterclockwise direction in the construction illustrated, will first release the shifter bar 110 and only then cause the throw 89 of the main shifter cam to engage the follower 91 and thereby move the shifter 60, it will be seen that the tail 144 will hit the obstruction wall 143 unless the compensator shifter 110 has reached its release position. Its relatively slow movement in this direction, as controlled by the dash-pot, allows ample time for the wear compensators to reach their positions of engagement with levers 42. Of course, when the tail hits the wall 143, further movement of the knob 5 is prevented, and actuation of the shifter 60 by cam throw 89 is withheld.

Arm 142 of the lever 140 has its endwise portion configurated to constitute a latch 146 positioned for cooperation with an ear 147 carried by the cam shifter 110, so as to hold the shifter 110 in advanced position in which the wear compensators are backed away from linkage levers 42. Lever 140 is biased so that the arm 142 is normally in latching position by means of a spring member 148 which is coiled about a spool 149, the latter being fixed upon the face of lever 140 and supported by the operating rod 80. One end of the spring 148 is hooked upon the lever 140, while the other is hooked to an ear 150 bent from the side wall of the shifter channel 60. As the operating rod 80 is moved by knob 5, pin 145 on the arm 122 swings the latch arm 142 toward unlatching position at the same time that the tail 144 approaches the obstruction wall 143. Counter rotation of lever 140, under the influence of spring 148, is limited by abutment of the rear edge of arm 141 against the follower roller 91. As the cam shifter 110 is advanced by means of the arm 122 pushing upon the pin 124, the shifter latches itself so as to remain in advanced position until released by counter rotation of knob 5.

When the mechanism is idle, the parts are in the relative positions shown in Figure 9, the shifter bar 110 is latched, as just described, and the cam actuating fingers 115a have backed the compensator cams away from the linkage levers 42. The electrodes are engaged with one another, and some of the levers 42 are in different positions than others, depending upon the extent to which the electrodes have been previously worn away. At this time, the shifter 60 is in its idle or rest position, to which it has been driven by compression spring 77.

Rotation of the knob 5 at this time, in counterclockwise direction in the illustrated apparatus, causes the lever 122 to swing until its pin 145 reaches the edge of the arm 142 of lever 140. During this phase of movement, the cam shifter bar 110 is not moved by spring 128, because the bar is latched. However, further rotation of the knob 5 in the same direction causes the pin 145 to carry the latch arm 142 with it and thereby release the cam shifter bar 110, which now moves relatively slowly under the control of the dash pot. These rotational movements of the operating shaft have meanwhile caused the throw 89 of the main shifter cam to approach the follower 91, but not yet to move it.

As the shifter bar 110 recedes, the fingers 115a recede from the shoulders 120 of the compensating cams, and cams rotate under the influence of the springs 102 such that their peripheries approach and move into engagement with the edges of the levers 42. At this time, the cams will perhaps be in different positions, as shown in Figure 3, corresponding to the extent to which the wear of electrodes has allowed the different linkage levers to occupy different positions when the electrodes are engaged. The shifter 60 is, therefore, now operatively coupled with the levers. Continued rotation of the actuating knob 5 causes the throw 89 of the shifter cam to engage the follower 91 and, therefore, the main shifter 60 simultaneously drives all of the levers 42 and spaces the electrodes accordingly.

If the knob 5 is moved very rapidly from the starting position shown in Figure 9, then the latch 142 will release the cam shifter bar 110, but the tail 144 of the interlock 141 will come into abutment with the obstruction 143 and further rotation of the knob will be prevented until the cam shifter lever 110 has been allowed to complete its movement. After this, the tail 144 may pass the obstruction to cause the actuation of the main shifter 60 by cam 88. Forceful twisting of knob 5 may actually prevent longitudinal movement of the cam shifter bar because of the frictional engagement of the tail 144 with the obstruction wall, and this condition will prevail so long as the operator continues to hold the knob with such force. However, as soon as the knob is released, the shifter bar will move on, and the operator then is at liberty to continue the rotation and reset the gaps.

Upon completion of the resetting operation, the parts are in the relationship shown in Figure 7. At this time, the apparatus is ready to be operated electrically, and all of the gaps are of the desired width.

Movement of the control knob 5 in an opposite direction, i. e. clockwise, first causes the tail 144 to return over the end of the obstruction wall 143. The follower 91 reaches the dwell of the cam 88 and as it does so, the shifter 60 recedes under the influence of the spring 77. This permits the levers 42 to follow the wear compensating cams and allows the electrodes to approach one another, although at this particular phase of the operation, not all of the electrodes may be in actual engagement since some may have been worn in the preceding operation. Further rotation of the knob in the clockwise direction causes the arm 122 to approach and engage the stud 125 on the cam shifter bar 110, thereby advancing the fingers 115a until they cause disengagement of the wear compensating cams with the levers 42. Therefore, this movement releases the levers 60 completely, and allows all of the electrodes to come firmly into engagement with one another. Shortly after this occurs, the latch 142 is actuated to engage the ear 147 and thereby hold the shifter 110. Continued movement in this direction is prevented through abutment of the end of the slot 112 with the stud 111. At this time, the parts are in the position shown in Figure 9.

From the operation of the apparatus just described, it may be observed that a plurality of electrodes accurately may be spaced from one another uniformly regardless of their wear, and such accuracy may be maintained through the periodic resetting of the mechanism whereby the desirable conditions of uniformity are re-established to compensate for any electrode deteriora-

tion that may have occurred in a preceding period of operation. On the other hand, the same principles conveniently may be utilized in a single gap apparatus to re-establish, from time to time, optimum gap spacing for it.

Having described our invention, we claim:

1. A spark gap mechanism comprising; a pair of electrodes normally engageable with one another, means for separating the electrodes such that a spark gap is delineated therebetween, a shifter, means for moving the shifter a fixed distance, and a wear compensating member for coupling the shifter with the said electrode separating means when the electrodes are in engagement, whereby subsequent movement of the shifter through the fixed distance separates the electrodes a predetermined distance.

2. Spark gap mechanism comprising; cooperable spark electrodes normally engaged and being separable, linkage effective for separating the electrodes, a shifter, and a self-adjusting wear compensator biased to assume different positions of coactive engagement with the shifter and the linkage, depending upon the wear condition of the electrodes when the linkage is in a position corresponding to engagement of the electrodes, the said wear compensator being effective for transmitting shifter motion to the linkage, whereby movement of the shifter through a predetermined distance effects spacing of the electrodes a predetermined spark gap distance.

3. Spark gap mechanism comprising; cooperable spark electrodes normally engaged and being separable, linkage effective for moving one of the electrodes from the other, a shifter, means for moving the shifter a predetermined distance, a key biased to assume different positions of coactive engagement with the shifter and the linkage, depending upon the wear condition of the electrodes when the linkage is in position corresponding to engagement of the electrodes, and an interlock for rendering said shifter moving means ineffective until said key has assumed a position of coactive engagement with the shifter and the linkage.

4. Spark gap mechanism comprising; radiators carrying cooperating spark electrodes which are engageable with one another, a linkage effective for moving at least one of the radiators to thereby separate the electrodes, a shifter common to said linkage, and a self-adjusting key carried by the shifter, the said key being constructed to assume different positions of coactive engagement with the linkage, depending upon the wear condition of the electrodes of the respective pairs when the electrodes of the respective pairs engage one another, and means for moving the shifter through a predetermined distance whereby such motion is transmitted through the key and linkage to the movable radiator for spacing the electrodes a predetermined spark gap distance.

5. Spark gap mechanism comprising; cooperable spark electrodes normally engaged and being separable, linkage effective for separating one of the electrodes from the other, a shifter, means for moving the shifter a predetermined distance, and a self-adjusting wear compensator biased to assume different positions of coactive engagement with the shifter and the linkage, depending upon the wear condition of the electrodes when the linkage is in position corresponding to engagement of the electrodes with one another, whereby movement of the shifter causes the linkage to move one electrode from the other,

through the wear compensator, for spacing the electrodes a predetermined spark gap distance.

6. Spark gap mechanism comprising; a plurality of pairs of cooperable spark electrodes normally engaged and being separable, linkages effective for separating the electrodes of the respective pairs, a shifter common to all linkages, self-adjusting wear compensators, one for each linkage, the said wear compensators being biased to assume different positions of coactive engagement with the shifter and the respective linkages, depending upon the wear conditions of the electrodes when the linkages are in positions corresponding to engagement of the electrodes, the said wear compensators being effective for transmitting shifter motion to the linkages, whereby movement of the shifter through a predetermined distance effects spacing apart of the electrodes of the pairs through a uniform predetermined spark gap distance.

7. Spark gap mechanism comprising; a plurality of cooperable spark electrodes arranged in pairs, the electrodes of each pair being normally engaged and being separable, linkages one for each pair of electrodes, for separating them, a shifter common to all of the pairs of electrodes, and self-adjusting keys for each pair of electrodes, the said keys being biased to assume different positions of coactive engagement with the shifter and the linkages respectively, depending upon the wear conditions of the electrodes when the linkages are in different positions corresponding to engagement of the electrodes of the respective pairs, whereby movement of the shifter through a predetermined distance effects spacing of the electrodes of the pairs a predetermined spark gap distance which is uniform in respect to all of the pairs of electrodes.

8. Spark gap mechanism comprising; electrodes normally engaged but separable to define a spark gap, a lever for moving one of the electrodes from the other, a shifter, means for moving said shifter through a predetermined distance, a self-adjusting key for coupling the shifter and the lever when the lever is in position corresponding to engagement of the electrodes, a time delay device for rendering said shifter means ineffective until the said key has coupled the shifter and the lever.

9. Spark gap mechanism comprising; spark electrodes normally engaged when the mechanism is idle and a resetting device for separating one electrode from the other a predetermined spark gap distance comprising, a lever for separating the electrodes, said lever assuming different positions when the electrodes are engaged, depending upon the wear condition of the electrodes, a shifter movable through a fixed distance, and a self-adjusting wedge adapted to position itself in coactive engagement with the shifter and the lever when the lever is in closed electrode position, whereby subsequent movement of the shifter through the predetermined distance will cause separation of the electrodes a predetermined distance independently of the wear condition of the electrodes.

10. Spark gap mechanism comprising; a plurality of pairs of spark electrodes connected in a series, the electrodes of the pairs normally being in engagement when the mechanism is idle, at least one electrode of each pair being movable, a shifter common to the movable electrodes of the plurality for moving them in unison, and means for moving the movable elec-

trodes of the plurality from engaged position a fixed distance which is common to them all.

11. Spark gap mechanism comprising; a plurality of pairs of spark electrodes connected in a series, the electrodes of the pairs normally being in engagement when the mechanism is idle, at least one electrode of each pair being movable, a shifter common to the movable electrodes of the plurality for moving them in unison, and means for moving the movable electrodes of the plurality from engaged position a fixed distance which is common to them all, said means including self-adjusting wear compensators, one for each pair of electrodes, said wear compensators being effective to couple the shifter with the movable electrodes after they have engaged one another.

12. Spark gap mechanism comprising; a pair of cooperating spark electrodes normally engageable, a shifter movable through a predetermined distance, means for moving the shifter through said distance, and means for separating the contacts including a self-adjusting key responsive to the movement of the shifter and effective for separating the contacts from engagement a predetermined distance proportioned to said first named predetermined distance.

13. A spark gap mechanism comprising; a pair of electrodes normally engageable with each other, means for separating the electrodes to form a spark gap therebetween, a primary shifter, a wear compensating member on said shifter for coupling the same to said electrode separating means when the electrodes are in engagement whereby movement of the shifter separates the electrodes a predetermined distance, a secondary shifter movable relative to the primary shifter and engageable with said gear compensating member to retract the member out of engagement with the separator means when the electrodes are in engagement to reset the compensating members, a common actuating shaft connected to said primary and secondary shifters, and arranged to be manually rotated to actuate the shifters, said actuating shaft being operable to actuate the primary shifter to separate the electrodes when the shaft is rotated in one direction and operable to actuate the secondary shifter to retract the compensating members when the shaft is rotated in the opposite direction.

14. A spark gap mechanism comprising; a pair of electrodes normally engageable with each other, means for separating the electrodes to form a spark gap therebetween, a primary shifter, a wear compensating member on said shifter for coupling the same to said electrode separating means when the electrodes are in engagement whereby movement of the shifter separates the electrodes a predetermined distance, a secondary shifter movable relative to the primary shifter and engageable with said wear compensating member to retract the member out of engagement with the separator means when the electrodes are in engagement to reset the compensating members, a common actuating shaft for said primary and secondary shifters, a cam on said shaft connected to the primary shifter to actuate the same, a lever arm on said shaft engageable with the secondary shifter to actuate the same, said cam being operable to actuate the shifter to separate the electrodes when the actuating shaft is rotated in one direction and said lever arm being operable to actuate the secondary shifter to retract the com-

pensating members when the shaft is rotated in the opposite direction.

15. A spark gap mechanism comprising; a pair of electrodes normally engageable with each other, means for separating the electrodes to form a spark gap therebetween, a primary shifter, a wear compensating member on said shifter for coupling the same to said electrode separating means when the electrodes are in engagement whereby movement of the shifter separates the electrodes a predetermined distance, a secondary shifter movable relative to the primary shifter and engageable with said wear compensating member to retract the member out of engagement with the separator means when the electrodes are in engagement to reset the compensating members, a common actuating shaft connected to said primary and secondary shifters and arranged to be manually rotated to actuate the shifters, said actuating shaft being operable to actuate the primary shifter to separate the electrodes when the shaft is rotated in one direction and operable to actuate the secondary shifter to retract the compensating members when the shaft is rotated in the opposite direction, latch means engageable with the secondary shifter to latch the shifter in retracted position, and a latch release member on said shaft engageable with the latch means to release the secondary shifter when the actuating shaft is rotated in the direction to separate the electrodes.

16. A spark gap mechanism having respective pairs of spark gaps constituting movable and stationary electrodes and having a primary shifter connected in common to all of said movable electrodes, means for establishing a wear compensating connection between the primary shifter and the movable electrodes, a secondary shifter arranged to reset said wear compensating means, an actuating shaft common to said primary and secondary shifters, a cam secured upon said shaft, a cam follower secured upon said primary shifter, said cam having a throw adapted to retract the primary shifter to separate the electrodes when the actuating shaft is rotated in one direction, means on said actuating shaft engageable with said secondary shifter to retract the same to reset the wear compensator means when the actuating shaft is rotated in the opposite direction with the electrodes in engagement, a latch arm engageable with the secondary shifter to latch the same in retracted position when the actuating shaft is rotated to the limit of its retracting movement, spring means for urging said secondary shifter in the opposite direction, and a trip member on said shaft engageable with said latch member to release the secondary shifter when the shaft is rotated in the opposite direction.

17. Spark gap mechanism comprising; respective pairs of electrodes, one electrode of each pair being stationary and the other being movable relative to the first, a respective lever operatively connected to each of said movable electrodes, a primary shifter for actuating said respective levers unitarily in a direction to separate said respective electrodes to form a spark gap, a wear compensating key for each of said levers mounted on said primary shifter for coupling the shifter to the respective levers when the shifter is in a position corresponding to engagement of the respective electrodes, a secondary shifter mounted for longitudinal movement relative to the primary shifter, means on said secondary shifter for engaging said compensating keys to retract said keys to reset the same when the primary shifter

is in electrode engaging position, an actuating shaft common to the primary and secondary shifters, a cam fixed on said shaft, a cam follower fixed on said primary shifter engageable with said cam to shift the primary shifter in electrode separating direction when the actuating shaft is rotated, and a shifter arm secured to said actuating shaft and engageable with said secondary shifter to shift the same in key retracting direction when the actuating shaft is rotated in the opposite direction, said cam having a dwell portion for maintaining the primary shifter in electrode engaging position during rotation of the actuating shaft in key retracting direction.

18. Spark gap mechanism comprising; respective pairs of electrodes, one electrode of each pair being stationary and the other being movable relative to the first, a respective lever operatively connected to each of said movable electrodes, a primary shifter for actuating said respective levers unitarily in a direction to separate said respective electrodes to form a spark gap, a wear compensating key for each of said levers mounted on said primary shifter for coupling the shifter to the respective levers when the shifter is in a position corresponding to engagement of the respective electrodes, a secondary shifter mounted for longitudinal movement relative to the primary shifter, means on said secondary shifter for engaging said compensating keys to retract said keys to reset the same when the primary shifter is in electrode engaging position, an actuating shaft common to the primary and secondary shifters, a cam fixed on said shaft, a cam follower fixed on said primary shifter engageable with said cam to shift the primary shifter in electrode separating direction when the actuating shaft is rotated, and a shifter arm secured to said actuating shaft and engageable with said secondary shifter to shift the same in key retracting direction when the actuating shaft is rotated in the opposite direction.

19. A spark gap mechanism having respective pairs of spark gaps constituting movable and stationary electrodes and having a primary shifter connected in common to all of said movable electrodes, means for establishing a wear compensating connection between the primary shifter and the movable electrodes, a secondary shifter arranged to reset said wear compensating means, an actuating shaft common to said primary and secondary shifters, a cam secured upon said shaft, a cam follower secured upon said primary shifter, said cam having a throw adapted to retract the primary shifter to separate the electrodes when the actuating shaft is rotated in one direction, a shifter arm on said actuating shaft engageable with said secondary shifter to retract the same to reset the wear compensator means when the actuating shaft is rotated in the opposite direction with the electrodes in engagement, a latch arm engageable with the secondary shifter to latch the same in retracted position when the actuating shaft is rotated to the limit of its retracting movement, spring means for urging said secondary shifter in the opposite direction, dash pot mechanism for controlling said spring urged movement, and a trip member on said shaft engageable with said latch member to release the secondary shifter when the actuating shaft is rotated in the direction to separate the electrodes.

20. A spark gap mechanism comprising; a pair of electrodes normally engageable with each other, means for separating the electrodes to

form a spark gap therebetween, a primary shifter, a wear compensating member on said shifter for coupling the same to said electrode separating means when the electrodes are in engagement whereby movement of the shifter separates the electrodes a predetermined distance, a secondary shifter movable relative to the primary shifter and engageable with said wear compensating member to retract the member out of engagement with the separator means when the electrodes are in engagement to reset the compensating members, a common actuating shaft connected to said primary and secondary shifters, and arranged to be manually rotated to actuate the shifters, said actuating shaft being operable to actuate the primary shifter to separate the electrodes when the shaft is rotated in one direction and operable to actuate the secondary shifter to retract the compensating members to a resetting position when the shaft is rotated in the opposite direction, mechanism for returning the secondary shifter at a controlled rate when the shaft is rotated in the direction to separate the electrodes, and an interlock on said shaft to lock the same against rotation until the secondary shifter has returned from the resetting position to prevent separation of the electrodes until the wear compensating member has reestablished a coupling between the primary shifter and the electrode separating means.

21. A spark gap mechanism having respective pairs of spark gaps constituting movable and stationary electrodes and having a primary shifter connected in common to all of said movable electrodes, means for establishing a wear compensating connection between the primary shifter and the movable electrodes, a secondary shifter arranged to reset said wear compensating means, an actuating shaft common to said primary and secondary shifters, a cam secured upon said shaft, a cam follower secured upon said primary shifter, said cam having a throw adapted to retract the primary shifter to separate the electrodes when the actuating shaft is rotated in one direction, a shifter arm on said actuating shaft engageable with said secondary shifter to retract the same to reset the wear compensator means when the actuating shaft is rotated in the opposite direction with the electrodes in engagement, a latch arm engageable with the secondary shifter to latch the same in retracted position when the actuating shaft is rotated to the limit of its retracting movement, with the wear compensating means in resetting position, a trip member on said shaft engageable with said latch member to release the secondary shifter when the actuating shaft is rotated in the direction to separate the electrodes, mechanism for returning the secondary shifter at a controlled rate when the trip member is released and an interlock on the actuating shaft to lock the same against rotation until the secondary shifter has returned from its resetting position to prevent separation of the electrodes until the wear compensating means have restablished a connection between the primary shifter and the movable electrodes.

22. A spark gap mechanism having respective pairs of spark gaps constituting movable and stationary electrodes and having a primary shifter connected in common to all of said movable electrodes, means for establishing a wear compensating connection between the primary shifter and the movable electrodes, a secondary shifter arranged to reset said wear compensating

means, an actuating shaft common to said primary and secondary shifters, a cam secured upon said shaft, a cam follower secured upon said primary shifter, said cam having a throw adapted to retract the primary shifter to separate the electrodes when the actuating shaft is rotated in one direction, a shifter arm on said actuating shaft engageable with said secondary shifter to retract the same to reset the wear compensating means when the actuating shaft is rotated in the opposite direction with the electrodes in engagement, a latch arm engageable with the secondary shifter to latch the same in retracted position when the actuating shaft is rotated to the limit of its retracting movement, a trip member on said shaft engageable with said latch member to release the secondary shifter when the actuating shaft is rotated in the direction to separate the electrodes, mechanism for return-

ing the secondary shifter at a controlled rate of movement, and a tail piece on said latch member engageable with a portion of secondary shifter to prevent rotation of the actuating shaft and separation of the electrodes until the secondary shifter has returned to a position to establish wear compensating connection between the primary shifter and the movable electrodes.
